UNITED STATES PATENT OFFICE.

CHARLES WIEBKE, OF NEWARK, NEW JERSEY.

BUTTON-COVERING MACHINE.

No. 915,141.

Specification of Letters Patent. Patented March 16, 1909.

Application filed August 24, 1906. Serial No. 331,882.

To all whom it may concern:

Be it known that I, CHARLES WIEBKE, a citizen of the United States, residing at Newark, in the county of Essex and State of New Jersey, have invented certain new and useful Improvements in Button-Covering Machines, of which the following is a specification, reference being had therein to the accompanying drawings, forming a part thereof.

10 My invention relates to button covering machines wherein a mold or form is covered by the winding of silk or other suitable covering material thereon, and has for its objects the ready adjustment of the positions 15 of the parts of the machine and also the ready adjustment of the speed of the mold carrying part.

My invention also has for its objects simplicity of construction, ease and reliability 20 of operation.

Other objects of my invention will appear from the following description of the machine embodying my invention illustrated in the accompanying drawings.

25 I will now describe such construction and will thereafter point out my invention in claims.

Figure 1 is an end elevation of the button covering machine, partly in section. Fig. 30 1^a is a detail elevation of the flat springs of the tension device. Fig. 2 is a front side elevation of the machine. Fig. 3 is a plan view. Fig. 4 is a detail plan view, partly in section, 35 of the mold actuating mechanism. Figs. 5 and 6 are enlarged views of the swiveling bearing for the mold spindle. Fig. 7 is an enlarged view of the knurled friction wheel. Fig. 8 is an enlarged rear face view of a portion of the grooved friction disk.

40 The several parts of the machine are shown as supported upon a base 1. The standard 2 for the winding flier is bolted to this base between guide-ways on the base in the usual manner and is forked at its upper 45 end, and the flier spindle 5 is removably and adjustably held in a sleeve 9 having bearings in these forks 3 and 4, a set-screw 14 clamping the flier spindle in desired position in the sleeve. The flier spindle 5 is provided at its 50 front end with an enlarged portion 6 in which the shank or longitudinal portion of the flier 7 is fitted in a bore at one side of the axis of the flier spindle, and the flier is removably and adjustably held in this enlarged portion 55 6 by a set-screw 13. The outer portion of the flier is curved through a semicircle and is

provided with a hook or loop 8 at the end of its curved portion and the front end of the flier.

A pulley 10 is provided upon the sleeve 9 60 of the flier spindle 5, and this pulley receives motion from a large driving pulley 12 by means of a cord 11 passing over both pulleys. The driving pulley 12 is fitted upon the driving shaft 15, and the driving shaft rotates in 65 bearings provided at the upper ends of standards 16, 17 which extend upward from the base and are bolted to the base between guide-ways in the usual manner. A hand crank 18 is shown secured upon the front end 70 of the shaft for manually operating the machine.

The button or mold carrier comprises a mold spindle 23, the lower portion of which is cylindrical and the upper portion of which is 75 gradually tapered to a point so that the mold may be readily inserted thereon and pressed downward until it is tightly gripped by the tapered surface of the spindle and molds having holes of different sizes may be carried 80 upon the mold spindle. The mold 49 is shown upon the spindle in Figs. 1 and 3. The cylindrical part of the mold spindle 23 is 85 removably and adjustably held within a sleeve 28 being clamped in the position to which it is adjusted by a set-screw 31, and this sleeve 28 is rotatably held in two arms 25, 25, on a swiveling frame comprising these arms and a ring 24 (Figs. 5 and 6) fitted to 90 swivel on a boss 20 of a bracket 19, this bracket being shown as secured to and projecting forward from the standard 2, which carries the flier. The movement of this 95 swiveling frame 24, 25, upon the bracket 19, permits the axis of the mold carrier to be inclined at the desired angle for holding the mold relatively to the flier. A set-screw 39 holds the swiveling frame in the position to which it has been adjusted.

The mold carrier is actuated from the 100 driving shaft 15 through motion-transmitting means including a longitudinally arranged intermediate shaft 21 which at its end in proximity to the mold carrier rotates in a bearing in the boss 20 of the bracket 19, 105 and has secured upon it at its end a beveled gear 26 which meshes with a beveled gear 27 secured upon the sleeve 28 of the mold carrier. The intermediate shaft 21 at its other end terminates just below the driving shaft 110 15 and rotates in a reduced bearing in a spring pin 45, which projects rearward from

a bearing stud 42 of a driving disk 30 and which extends through this stud and projects forward therefrom and has a helical spring 47 surrounding it. The spring bears 5 at its rear end against the front end of the stud 42 and at its front end against the rear face of an adjusting nut 48 on the spring pin 45. Thus the spring 47 provides a yielding bearing for the intermediate shaft 21; and 10 to provide for the movement of the shaft thus permitted the shaft-bearings are loosely fitted. The purpose of the yielding means for carrying the intermediate shaft 21 is to permit the actuation of this shaft by engagement 15 with the driving disk 30 of a motion-receiving disk 29 carried by this shaft, and to permit the motion-receiving disk 29 to be adjusted to engage the driving disk 30 at different distances from the axis of the disk 20 so as to vary the speed imparted to the intermediate shaft from the driving disk. The motion-receiving disk 29 is free to slide longitudinally upon the intermediate shaft 21, its boss having a set-screw 32 which enters 25 a longitudinal slot 33 in the intermediate shaft so as to hold it rotatively to the shaft, but permit it to move longitudinally upon the shaft. The rear face of the driving disk 30 is provided with a number of concentric 30 grooves 30^a, and the motion-receiving disk 29 is tapered to an edge and knurled at its periphery so that it will enter any one of these grooves and, under tension of the spring 47, will be held tightly therein against the 35 driving disk so as to be rotated by the driving disk. The motion-receiving disk 29 is separately shown in Fig. 7. This thin edge permits the circular grooves 30^a in the driving disk to be arranged quite closely together 40 and thus assures an even adjustment. To shift it from one groove to another it is only necessary to press the spring pin 45 backward, thereby compressing the spring 47 and motion-receiving disk backward away 45 from the rear face of the driving disk and then to slide the motion-receiving disk longitudinally on the intermediate shaft to the desired new position of adjustment. Upon releasing the spring pin the spring 50 restores the motion-receiving disk to engagement with the driving disk in the groove thereof to which it has been adjusted and the motion-receiving disk will be held in such groove until moved therefrom by an intentional act of adjustment.

To relieve the bearing of the driving disk 30 from the thrust of the motion-receiving disk, an idle roller 34 bears against the front face of the driving disk in proximity to the 60 outer periphery of this disk, and this idle roller is carried on a stud 35 secured to the standard 16, which carries the bearing stud 42 of the driving disk. The bearing stud 42 is provided with an annular collar 43 and is 65 secured in place by a nut 44. The driving

disk 30 is shown as actuated from the driving shaft 15 through a toothed pinion 41 on the driving shaft meshing in an intermediate gear wheel 37 and a toothed pinion 38 secured to the gear wheel 37 meshing in the teeth on 70 the periphery of the driving disk 30.

The feeding and guiding means for the silk or other covering material comprise a spool 50, which rotates upon a stud 51 mounted upon an arm 52 secured to and extending 75 rearwardly from the base. To ease the unwinding of the silk, a rotary flier is provided comprising an arm 53 carried by a hub 56 fitted to rotate freely upon the upper portion of the stud 51, this arm 53 having an eye 55 80 at its free end which guides the silk in the unwinding movement thereof. The silk passes from the rotating eye 55 upward and over a guide-loop in an arm 60 extending up from the frame and then downward and through 85 an eye in an arm 61 extending upward from an arm 58 projecting rearward from the standard 2. The silk then passes through a tension device comprising two flat springs 57 clamped at their lower extremities to the arm 90 58 and also clamped together by a yoke 59 which is adapted to be moved up or down along the length of the tension springs to vary the tension of the springs. From the tension device the silk enters the longitudinal 95 opening in the flier spindle 5 and passes forward through this opening and from the front end of the flier spindle passes to the loop 8 of the flier, and from the loop 8 of the flier it passes around the mold 49 upon 100 which it is wound by the flier to cover the mold.

An exact adjustment of the flier and mold carrier is required for the proper covering of the mold. This may be very readily effected 105 as the flier spindle 5 may be adjusted longitudinally or axially in its carrying sleeve 9 by manipulation of the set-screw 14, and the radial length of the flier may be independently adjusted by manipulation of the set-screw 18; and the mold spindle may be adjusted longitudinally or axially in its carrying sleeve by manipulation of the screw 31, and the angular position of the mold carrier may be adjusted by manipulation of the set-screw 39. The independence of these several 110 means of adjustment permits each adjustment to be performed without disturbance of any other adjustment, and thus enables the operator to very readily make the necessary 115 changes for each variation of mold. Thus the machine may be very readily changed for covering buttons of different sizes and with molds of different shapes. The speed adjustment is also very readily and 120 quickly performed by manipulation of the spring pin 47 and motion-receiving disk 29 in the manner already described.

It is obvious that various modifications may be made in the construction shown and 130

above particularly described within the principle and scope of my invention.

I claim as my invention:

1. A button covering machine comprising
5 a mold carrier, flier-actuating mechanism
and a winding flier, the winding flier including
a spindle, a flier arm carried by the spindle,
a sleeve carrying the spindle, the flier-actuating
mechanism being connected to the sleeve,
10 the spindle being adapted to be moved axially
in the sleeve, and means for locking the
spindle against axial movement.

2. A button covering machine comprising
a mold carrier and a winding flier, the flier
15 being adapted to be moved axially, the flier
including means for locking the flier against
axial movement, and the mold carrier being
adapted to be moved relatively to the flier
and including means for locking the mold
20 carrier against such movement.

3. A button covering machine comprising
a mold carrier and a winding flier, the mold
carrier including an axially-movable rotating
mold spindle and means for locking the mold
25 spindle against axial movement.

4. A button covering machine comprising
a mold carrier and a winding flier, the mold
carrier including a mold spindle adapted to be
moved both axially and angularly and means
30 for locking the mold spindle against axial
movement and means for locking the mold
spindle against angular movement.

5. A button covering machine comprising
a mold carrier and an axially and radially
35 movable winding flier, the flier including
means for locking it against axial movement
and also including means for locking it
against radial movement.

6. A button covering machine comprising a
40 winding flier adapted to be moved both axi-
ally and radially, and a mold carrier movable
to different positions relatively to the flier,
the flier including means for locking the flier
against axial movement and also including
45 means for locking it against radial move-
ment, and the mold carrier including means
for locking the mold carrier against such
relative movement.

7. A button covering machine comprising
50 a mold carrier and a winding flier, the flier
being adapted to be moved both axially and
radially, the flier including means for locking
it against axial movement and also including
means for locking it against radial move-
55 ment, and the mold carrier being adapted
to be moved axially and including means for
locking it against axial movement.

8. A button covering machine comprising
a mold carrier and an axially and radially
60 movable winding flier, the flier including
means for locking the flier against axial
movement and means for locking the flier
against radial movement, and the mold car-
rier including an axially and angularly mov-
65 able mold spindle and means for locking the

mold spindle against axial movement and
means for locking the mold spindle against
angular movement.

9. A button covering machine comprising
a mold carrier and a winding flier, the wind- 70
ing flier including a spindle, a flier arm mov-
ably mounted thereon, means for locking the
flier arm against movement relatively to the
spindle, a sleeve carrying the spindle, the
spindle being adapted to be moved axially in 75
the sleeve, and means for locking the spindle
against such axial movement.

10. A button covering machine comprising
a mold carrier and a winding flier, the mold 80
carrier including a mold spindle, a sleeve car-
rying the spindle, the spindle being mounted
for axial movement in the sleeve, and means
for locking the spindle against axial move-
ment.

11. A button covering machine comprising 85
a mold carrier and a winding flier, the mold
carrier including a mold spindle, a sleeve car-
rying the spindle, the spindle being mounted
for axial movement in the sleeve, means for
locking the spindle against axial movement, 90
a swiveling bearing for the sleeve, and means
for locking the bearing against swiveling
movement.

12. A button covering machine comprising
a mold carrier and a winding flier, the wind- 95
ing flier including a spindle, a flier arm there-
on, a sleeve carrying the spindle, the spindle
being adapted to be moved axially in the
sleeve, and means for locking the spindle
against axial movement, and the mold car- 100
rier including a mold spindle, a sleeve carry-
ing the spindle, the mold spindle being adapt-
ed to be moved axially in its sleeve, and
means for locking the mold spindle against
such axial movement. 105

13. A button covering machine comprising
a mold carrier and a winding flier, the wind- 110
ing flier including a spindle, a flier arm there-
on, a sleeve carrying the spindle, the spindle
being adapted to be moved axially in the
sleeve, and means for locking the spindle
against axial movement, and the mold car-
rier including a mold spindle, a sleeve carry-
ing the spindle, the mold spindle being adapt-
ed to be moved axially in its sleeve, means 115
for locking the mold spindle against such
axial movement, a swiveling bearing for the
mold carrier sleeve, and means for locking
the bearing against swiveling movement.

14. A button covering machine compris- 120
ing a mold carrier and a winding flier, the
winding flier including a spindle, a flier arm
thereon and adapted to be moved relatively
thereto, means for locking the flier arm
against such movement, a sleeve carrying 125
the spindle, the spindle being adapted to be
moved axially in the sleeve, and means for
locking the spindle against axial movement,
and the mold carrier including a mold spin-
dle, a sleeve carrying the mold spindle, the 130

mold spindle being adapted to be moved axially in the sleeve, and means for locking the mold spindle against axial movement.

15. A button covering machine comprising a mold carrier and a winding flier, the winding flier including a spindle, a flier arm thereon and adapted to be moved relatively thereto, means for locking the flier arm against such movement, a sleeve carrying the spindle, the spindle being adapted to be moved axially in the sleeve, and means for locking the spindle against axial movement, and the mold carrier including a mold spindle, a sleeve carrying the mold spindle, the mold spindle being adapted to be moved axially in its sleeve, means for locking the mold spindle against axial movement, a swiveling bearing for the mold carrier sleeve, and means for locking the bearing against swiveling movement.

16. A button covering machine comprising a winding flier, a mold carrier, a driving disk having a plurality of concentric circular grooves at different distances from the axis thereof, an intermediate shaft connected to the mold carrier to impart rotation thereto, a motion-receiving disk connected to the intermediate shaft to rotate therewith but be movable longitudinally relatively thereto, such motion-receiving disk being engageable in any one of the grooves of the driving disk to receive rotative movement from the driving disk, and yielding means controlling the intermediate shaft to permit the shifting of the motion-receiving disk into engagement with different grooves of the driving disk and to hold the motion-transmitting disk in contact with the driving disk when thus engaged.

17. A button covering machine comprising a winding flier, a mold carrier, a driving disk, an intermediate shaft connected to the mold carrier to impart rotation thereto, a motion-receiving disk connected to the intermediate shaft to rotate therewith but be movable longitudinally relative thereto, and a spring-pin providing a bearing for the intermediate shaft and operative to hold the motion-receiving disk in motion-receiving contact with the driving disk and to permit

the motion-receiving disk to be engaged with the driving disk at any one of a number of different distances from the axis of the driving disk.

18. A button covering machine comprising a winding flier, mechanism for actuating the flier having provision for adjusting the flier longitudinally with respect to its axis of rotation, a mold carrier, and mechanism for supporting and rotating the mold carrier about an axis inclined to the axis of rotation of the flier, said supporting mechanism having provision for angular adjustment of the mold carrier.

19. A button covering machine comprising a winding flier, and a tapered and longitudinally adjustable mold carrier arranged in operative relation with the winding flier.

20. A button covering machine comprising a winding flier, means for rotating the flier, a tapered mold carrier, and mechanism for supporting and rotating the mold carrier, and mechanism for supporting and rotating the mold carrier about an axis inclined to the axis of rotation of the flier, said mechanism having provision for longitudinal adjustment of the mold carrier.

21. A button covering machine, comprising a winding flier, a mold carrier, a driving disk having a plurality of concentric circular grooves at different distances from the axis thereof, an intermediate shaft connected to the mold carrier to impart rotation thereto, a motion-receiving disk connected to the intermediate shaft to rotate therewith but be movable longitudinally relatively thereto, and a spring-pin providing a bearing for the intermediate shaft and operative to hold the motion-receiving disk in motion-receiving contact with the driving disk and to permit the motion-receiving disk to be shifted into engagement with different grooves of the driving disk.

In testimony whereof I have affixed my signature in presence of two witnesses.

CHARLES WIEBKE.
